ARTICLE OF FURNITURE

Charles E. Friesner, Toledo, Ohio, assignor to The Hetrick Manufacturing Company, Toledo, Ohio, a corporation of Ohio

Application December 4, 1933, Serial No. 700,773

1 Claim. (Cl. 155—182)

This invention relates to articles of furniture such as gliders, chairs, and similar furniture used on porches, lawns, and the like, but is particularly concerned with the mounting of the cushions on the back of such furniture.

Heretofore, it has been customary to attach cushions to the backs of gliders by using screws or bolts, which are inserted through the flexible covering of the backs and fastened to the frame, which is usually of metal, such as angle iron. This is objectionable from several standpoints. It is a time-consuming operation to mount the cushions, but particularly from the standpoint of the user, it is troublesome, and requires time and tools to remove the fasteners. It is to be understood that where furniture of this type is used out-of-doors, it is desirable that both the seat and back cushions be readily removable so that they can be taken under cover in the event of rain, and since the frames are usually heavy and cumbersome, the cushions should be removable.

It is an object of this invention to overcome the above difficulties and to provide a mounting for the back cushions to enable them readily and conveniently to be mounted and removed without the use of special tools.

Another object is to produce a new and improved mounting for a cushion on a frame having the features of construction and arrangement hereinafter described.

Further objects will hereinafter appear, and, for purposes of illustration, but not of limitation, an embodiment of the invention is shown on the accompanying drawing, in which:

35 Figure 1 is a perspective view of a glider with a portion of the seat and back cushions broken away;

Figure 2 is an enlarged sectional view on the plane 2—2 of Figure 1;

40 Figure 3 is a top plan view of a portion of the back cushion showing the connection with the frame; and

Figure 4 is a perspective view of one of the hook members or clips.

45 The illustrated embodiment of the invention comprises a glider having a supporting frame 10, and seat and back frames 11 and 12, respectively. The seat frame is hung from the supporting frame 10 by a pair of U-shaped cradle bars 13, and the back 12 is held in its upwardly disposed position by braces 14. Covering the seat frame 11 is a cushion 15, and covering the back is a cushion 16. The cushions consist of any suitable flexible

55 covering, such as canvas, leather imitations, etc.,

stuffed with cotton, kapok, or any other suitable material.

In this instance the back frame 12 is provided at its upper ends with a horizontally disposed angle iron 17 having a rearwardly extending 60 horizontally disposed strip or bar 18, as shown particularly in Figure 2. Since the remainder of the frame forms no part of the present invention, detailed description thereof is not deemed necessary.

Forming a part of the back cushion 16 and co-extensive therewith is a tab 19, which is formed of a continuation of the upper edge portion of the cushion 16, which is folded upon itself and suitably secured, as by sewing, to the rear side of the 70 cushion, thereby providing a pocket 20, which extends rearwardly from the upper edge portion of the cushion 16 the inner side of the pocket having two plies which engage over the inner corner or side edge of the glider bar 17. Inserted in the 75 pocket 20 is an elongate strip 21 of relatively stiff material, such as strap metal, this strip being substantially co-extensive with the pocket 20 and extending entirely across the back cushion. If desired, the ends of the pocket 20 may be closed 80 by sewing, thereby to provide a finished appearance to the cushion. A series of holes are formed at spaced intervals in the strip 21, and fasteners or staples 22, having an enlarged head, are forced through openings provided in the tab 19 and 85 through the holes in the strip 21, the opposite ends of the staples being inserted through holes 23 in metal hooks or clips 24, the free ends of the staples being bent outwardly in opposite directions, as indicated at 25.

It will be noted that the clips or hooks 24 each have a hooked portion 26 engageable over the free end of the strip or bar 18 of the angle iron 17. The inner ends of the clips underlie the pocket and seat directly on the glider bar.

90 In practice, the cushion 16 is placed on the back frame 12, and thereafter by pulling rearwardly on the tab 19 the hooks 26 can be slipped over the free edge of the bar 18, the resilience of the cushion being sufficient to retain the hooks 100 properly in engagement with the bar. It is manifest that the back cushion can be readily and conveniently detached almost instantaneously without the use of tools, but when in use, the cushion is held in the desired position. The seat 105 cushion, if desired, may abut against the lower portion of the back cushion 16, thereby securely to hold this part in place, although the weight of the cushion is ordinarily sufficient for the purpose.

It is to be understood that numerous changes in details of construction, arrangement and operation may be effected without departing from the spirit of the invention, especially as defined in the appended claim.

What I claim as new and desire to secure by Letters Patent is:

A back cushion for gliders of the type having a back provided with an elongate rearwardly projecting horizontal bar at the upper edge of the back, composed of a cushion member having a cover provided at its top edge with an extension

which is doubled upon itself and sewed at its outer edge to the cover at the back of the cushion thereby to provide a pocket composed of two plies which each at their inner sides extend over the inner side edge of the glider bar, a stiff strip in the pocket, and a series of clips secured to the strip and having inner ends which underlie the pockets and seat directly on the glider bar and having outer ends which are curved to engage over and beneath the outer side edge of the bar.

CHARLES E. FRIESNER.
